LOOSE-LEAF BINDER

Atto N. Hanna, Newark, N. J.

Application August 3, 1938, Serial No. 222,762

8 Claims. (Cl. 129—10)

The invention relates to loose leaf binders, and more particularly to a binder of the type in which pivotally connected arcuate post carrying members are superimposed one upon the other and pivotally connected at one end so as to permit the simultaneous separation of all of the posts for the purpose of inserting or removing sheets from those collected upon loops formed by said arcuate posts.

The general type of binder above referred to is old and well known in the art, the invention relating more particularly to a binder in which each of the two separable members, including the arcuate posts carried by each such member and tongues carried by one of the members and engageable with the other member, may be formed from sheet metal. The construction and arrangement of said members is such as to prevent relative movement of the complementary portions of the loops formed by said arcuate posts to an extent to result in the disturbance of the alinement of adjacent or abutting end portions of the arcuate posts, or a distortion of the arcuate posts when these members are superimposed one upon the other. In this manner, accidental escape of a sheet from the posts not only is prevented, but likelihood of the tearing of a sheet when moving it from one arcuate post to another arcuate post is avoided.

In a binder embodying the invention, it is possible to employ a considerable number of posts and a considerable number of tongues upon each member without any increase in the cost of production of the binder as compared with the use of two sets of loops, an arrangement which for many years has been the common practice with binders of the general type to which the invention relates.

The construction is such that one of the post carrying members may be secured to the back board of a book binding and the other member may move toward and from the first named and fixed member when closing or opening the loops formed by the arcuate posts. In the binder, the tongues for preventing relative movement of the two members are formed upon the immovable or base member, thus permitting free pivotal movement of the movable member without likelihood of mutilating the edges of any of the sheets upon the other member, since these sheets are positioned and supported by said tongues above the plane of movement of the pivotal member.

While the tongues are spaced from the member carrying same a distance substantially coincidental with the thickness of the movable mem-

ber, so as to frictionally engage same, I provide co-operating locking means upon the two members to positively prevent accidental separation of the loops from the application of the weight of the contained sheets upon the movable member.

The confining tongues being formed from the metal along one edge of the fixed member, and the movable member being of substantially the same width as the fixed member, it is obvious that one edge of the movable member will, when the two members are closed together to form the loops, engage the curved portion of each tongue at the edge of the member carrying same. This not only limits the pivotal movement of said movable member, when closing the loops, so as to obviate all possibility of distortion of the arcuate posts by the exertion of excessive pressure upon the movable member, but with a locking mechanism such as is hereinafter described, the movable post carrying members may not only be held against accidental separation resulting in partial opening of the loops, but may be forced into engagement with the curved portion of the tongues and held in this position so as to avoid any possible play or lost motion between said members when the posts are closed.

The action of the locking mechanism when closing the two members is such as to develop stresses which will not only flex the tongues and wedge one edge of the movable member into the curved portion of the tongues, but will flex any posts, the ends of which abut each other before the two members are completely closed and locked, so as to permit other posts which have not reached the abutting position to be brought together.

In a binder embodying the invention, the ends of the posts upon different members are so formed as to overlap in a manner to produce substantial continuity in the loops formed by the arcuate posts, even though the ends of said posts may not be in close abutting relation.

In a binder embodying the invention, the members, including the integral arcuate posts and the tongues, are formed of half hard drawing sheet metal stock, and hence the posts and the tongues have little inherent resiliency.

In order to make the confining tongues more effective in holding the movable member in close abutting relation to the fixed member, I provide said movable member with a longitudinally extending rib or ribs, at least one of which, by engagement with the under face of the various tongues, will flex said tongues to an extent to

force the movable member into the desired close abutting relation with the fixed member. These ribs also act to stiffen the movable member.

The invention consists primarily in a loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue carried by one of said strips, and a hooked member pivotally supported upon the other of said strips and engageable with said tongue; and in such other novel features of construction and combination of parts as are hereinafter set forth and described, and more particularly pointed out in the claims hereto appended.

Referring to the drawing:

Fig. 1 is a longitudinally condensed plan view of a binder embodying the invention, with the loop carrying members in the closed position;

Fig. 2 is a similar view with the loop carrying members in the open position;

Fig. 3 is an end view of Fig. 1 showing the locking mechanism; and

Fig. 4 is a detailed perspective view of the adjacent ends of the two loop carrying members showing the locking mechanism in the inoperative position.

Like numerals refer to like parts throughout the several views.

In the embodiment of the invention shown in the drawing, the binder cover is shown at 10 and the back board thereof at 11. A base strip member 12 is permanently secured, by means of rivets 13 or otherwise, to said back board 11. This fixed base member 12 is formed by means of dies from a strip of sheet metal and has, along one edge thereof, a plurality of arcuate posts 14 formed integrally with the base strip proper and extending upwardly from, and part way across, the member 12.

Formed from the material of the base member 12 at the same edge thereof as the arcuate posts 14, are a plurality of tongues 15. These tongues 15 overlay the material of the base strip 12 and have a curved portion 16 passing from the flat portion of the tongues overlaying the strip, to the edge of the strip.

The flat portion of the tongues overlaying the base strip extends parallel with said strip and is spaced therefrom a distance substantially coincident with the thickness of a movable member pivoted to the strip and adapted to be superim-

posed thereon in a manner to be hereinafter referred to.

Associated with the base strip member 12 is a movable strip member 17, shorter in length than the base member 12 for a purpose to be hereinafter referred to.

The members 12 and 17 are connected by means of a pivot 18 positioned at one end of these strips. This movable member or strip 17 is of a thickness corresponding with the space between the base member or strip 12 and the lower face of the tongues, so that when the strip 17, by a pivotal movement, is superimposed upon the base strip 12, said movable strip will be held in close abutting relation to the fixed strip by the various tongues 15.

To compensate for any slight irregularities in the spacing of the different tongues 15 from the base strip 12, or any slight variation in the thickness 20 of the material of the strip 17, I provide said strip 17 with a raised rib 19 adapted to pass under, frictionally engage and upwardly flex a tongue or tongues 15 with the closing movement of the movable member or strip 17. This rib 19 projects above the top surface of the strip 17 only a few thousandths of an inch, but this is sufficient to secure the desired operative effects above referred to.

I also provide a second rib 20 adjacent the opposite longitudinal edge of the movable strip 17, the sole function of this being to stiffen the movable member adjacent the edge thereof from which the arcuate posts, complementary to the posts 14, project.

Along one edge of the movable strip 17 and formed integrally with said strip, is a sequence of arcuate posts 21 corresponding in configuration, number and position with the posts 14 upon the base strip 12.

Binders embodying the invention are made in different sizes, both as to the diameter of the loops formed by the arcuate posts and the width of the base and movable strips. The number of loops varies with different diameters of loops and different lengths of binders. With an eleven inch binder having approximately three-quarter inch loops there are ordinarily about eleven loops, spaced about one inch apart. With a six inch binder having loops about three-eighths of an inch in diameter, there are usually twelve loops spaced about a half inch apart. The number of loops and the spacing thereof, however, is not critical.

With smaller sized binders, an overlaying tongue 15 will be positioned midway between all of the loops excepting the two end loops, in order to provide sufficient space for the attachment means between the base strip and the back board of the cover. In binders having larger size loops, there is ordinarily a tongue located between all adjacent loops.

The relative position of the tongues and arcuate posts is largely a matter of facilitating economy in production of the base strip member.

In all sizes of binders, the ends of the various arcuate posts are so formed that the ends of the complementary posts forming each loop will overlap each other in a manner to avoid the formation of any gap at the meeting points of said ends.

In the form of the invention shown, this result is secured by means of a recess 22 in the arcuate posts 21 and a projection 23 upon the arcuate posts 14, said projection 23 being adapted to enter the recess 22. With this construction, a con-

tinuous surface is afforded throughout the loop, notwithstanding that the ends of the complementary posts may not be in close abutting relation. In this way, a gap extending completely across the loop at the meeting point of the ends of the two complementary arcuate posts is prevented.

With binders having loops of small size, flat metal stock may be used in the posts 14 and 21. In binders using larger loops, however, such as those shown in the accompanying drawing, it is preferable to provide a reinforcing rib 24 throughout each arcuate post, so as to impart a necessary stiffness to the post to prevent possible distortion of the loop by reason of the heavier weight of the leaves mounted thereon.

To prevent accidental movement of the movable strip 17 in a manner to permit the opening of any loop, I provide a locking mechanism which, when the strip 17 has been superimposed upon the strip 12, may be actuated to not only retain these strips in the closed position so long as this mechanism is set, but to complete the closing movement of the movable strip so as to engage the edge thereof adjacent the rib 19 with the curved portion 16 of the various tongues 15, and engage the ends of the complementary arcuate posts formed in each loop with each other, notwithstanding slight variation in the dimensions of the parts of the two members, or slight irregularity in the assembling of these members.

In the production of parts made of sheet metal and the assembly of standard parts made at different times, there is always likelihood of a slight variation in dimensions, particularly when these parts have to be tumbled and plated or otherwise decorated. There is also likelihood of slight variation in the thickness of the sheet metal used.

In a binder having a considerable number of loops along the length thereof, the complementary parts of which are carried by two strips pivoted at one end, the bringing of the ends of the various complementary posts forming each loop into the desired abutting relation with each other, offers considerable difficulty from a manufacturing standpoint, and slight variations in the position of the ends of the posts will tend to interfere with the proper closing of the loops. This is particularly true if the loops, adjacent the point of hinged connection between the strips, meet before the ends of the posts toward the opposite end of the strip.

It is possible, however, with a locking mechanism such as that shown in the drawing, to exert sufficient pressure upon the movable member to flex any prematurely engaged arcuate post sufficiently to permit all arcuate posts to have their ends brought into the desired engaging relation, and to hold the parts so as to maintain the posts in this position.

This locking mechanism, in the form of the invention shown, comprises a locking tongue 25 having a rounded end 26 projecting from the free end of the strip member 17 adjacent the edge thereof from which the arcuate posts 21 project upwardly and over the strip, this locking tongue having, toward its end, a nub 27 forced upwardly thereof. The locking tongue is offset upwardly in relation to the plane of the strip 17.

Pivottally mounted upon the base strip 12 is a locking member having a hooked portion 28 adapted to pass over and embrace the locking tongue 25. The nub 27 acts as a stop to interfere with accidental disengagement of the hooked end 28 from the locking tongue 25.

The hooked member 28 constitutes one arm of a bell crank lever, the other arm of which has a finger portion 29 turned at right angles to the plane of the hook so as to permit the locking member to be readily actuated by hand. The pivot connecting the locking member with the strip 12 is shown at 30.

The paper sheets to be mounted upon the binder loops must be pierced within the edge of the sheet a distance less than one-half of the width of the base strip 12 in order to permit a proper positioning of turned leaves. To avoid interference with turning of the leaves by the locking mechanism, the point of pivotal connection of the movable locking member upon the strip 12 is preferably at one side of the center line of the strip toward the edge of the strip opposite that from which the posts 14 and tongues 15 project.

By making the movable strip 17 shorter than the base strip 12, space is provided for the mounting of the movable member of the locking mechanism upon said base strip.

The operation of the herein described binder is substantially as follows:

The two members 12 and 17 and the locking member 28 to 30 are separately formed and finished by plating or enamelling, and subsequently assembled by means of the pivots 18 and 30. During the production or finishing of said member, there is possibility of slight distortion of some of the arcuate posts or of the tongues 15, any distortion of the latter always being in the nature of forcing one or more of the tongues to a position too close to the strip 12.

The binder, after assembly, is closed, and locked in the closed position and shipped to the bindery in this condition. There is always a possibility that some of the posts or of the tongues may be slightly displaced when riveting or otherwise securing the base member 12 to the back board of a book.

As in all sheet metal work, uniform accuracy of parts is impossible, and a binder embodying the present invention is so formed as to compensate for slight inaccuracies which will never exceed a few thousandths of an inch.

When the binder is to be used, pressure is exerted upon the finger grip 29 to disengage the hooked member 28 from the tongue 25, thus permitting movement of the movable strip 17 about the pivot 18 in a manner to expose the ends of the arcuate posts 14. Leaves of a number to form a book of the desired thickness are then threaded upon the various arcuate posts 14, each of these leaves being pierced by rectangular openings so spaced as to conform to the spacing of the posts 14. The openings in the leaves have dimensions to permit a free sliding fit between the leaves and the various arcuate posts.

It will be noted that the leaves mounted upon the posts rest upon and are supported by the various tongues 15, thus being spaced from the strip 12 a distance sufficient to permit the insertion of the strip 17 of the movable member beneath the tongues without engaging the edge of the lowermost sheet.

By embodying in the binder a considerable number of fairly closely positioned arcuate posts and supporting tongues 15, not only is a support provided for the bound leaves adequate to prevent likelihood of the tearing of the leaves about the posts, but sagging of the leaves between the various tongues in a manner to interfere with a free movement of the strip 17 in the manner above described, is prevented.

When all the leaves have been mounted upon the posts 14, the strip 17 is turned upon its pivot 18 until the edge thereof adjacent the rib 19 is in alinement with the edge of the strip 12 adjacent the posts and tongues of said strip. This swinging of the member 17 will engage the ends of the complementary arcuate posts 14 and 21, so as to form a substantially continuous loop from edge to edge of the strips 12 and 17.

If the ends of any of the posts toward the pivot 18 meet each other before the ends of other posts meet, it is obvious that further movement of the strip 17 will be prevented, except as a result of the displacement of the posts which have thus met prematurely. The nature of the metal stock permits such displacement of the posts.

When the movable member 17 is thus superimposed upon the strip 12 and between it and the tongues 15, the locking tongue 25 is within operative range of the hooked arm 28 of the locking member.

To hold the fixed member and the movable member in proper position in relation to each other under all conditions of use, and complete the closing of the various loops formed by the complementary arcuate posts, the hooked member is turned about its pivot 30 by the finger hold 29 until said hooked member passes over and embraces the locking tongue 25. If the ends of all of the posts on the strip 17 are not in closely abutting relation to those on the strip 12, the engagement of the hooked member with the rounded end 26 of the tongue 25 will develop a camming action of sufficient strength to flex any arcuate post which is not in the proper position and thus permit the ends of all of the posts to meet.

The final closing movement of the movable member 17 upon the fixed member 12, whether by pressing the member 17 by hand or by the camming action of the locking member above referred, will bring the edge of the strip 17 adjacent the rib 19 in close abutting position with the rounded portion 16 of each of the tongues 15, and thus wedge the member 17 tightly against the base member 12. This rounded portion also limits the pivotal movement of the strip 17 when closing the binder in the manner described, so as to preclude all possibility of accidental distortion of any of the posts by the development of excess stresses thereon.

By locating the tongue 25 adjacent the edge of the strip 17 from which the posts 21 project, and using a hook 28 embracing this tongue, any tendency toward a slight lifting of the end of the strip adjacent said tongue is prevented.

If any tongue 15 be positioned too close to the strip 12, the engagement of the rib 19 with that tongue will, by a wedging action, flex it upwardly, so that any displaced tongue, instead of interfering with the operation of closing the binder, will merely have the effect of more closely holding the strip 17 in abutting relation with the strip 12.

The rib 19 projects from the upper surface of the strip 17 by only a few thousandths of an inch, and the rest of this strip is such as to have a free sliding fit between the strip 12 and the tongues 15.

The nub 27 is merely for the purpose of preventing disengagement of the hook 28 and tongue 25 by accidental movement of the hook 28 of the locking member.

It is not my intention to limit the invention to the precise details of construction shown in the

accompanying drawing, it being apparent that such may be varied without departing from the spirit and scope of the invention.

Having described the invention, what I claim as new and desire to have protected by Letters Patent, is:

1. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue carried by one of said strips, and a hooked member pivotally supported upon the other of said strips and engageable with said tongue.

2. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue carried by one of said strips, and a hooked member pivotally supported upon the other of said strips and engageable with said tongue.

3. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlying, being parallel with and being spaced from

said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue projecting from the end, and upwardly offset from the plane, of said movable strip, and a locking member pivotally supported upon the other of said strips having a hooked arm adapted to embrace said tongue, said tongue having a nub adjacent its end whereby accidental disengagement of said hook from said tongue is prevented.

4. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue projecting from the end, and upwardly offset from the plane, of said movable strip, and a locking member pivotally supported upon the other of said strips having a hooked arm adapted to embrace said tongue and a finger piece for actuating said locking member.

5. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base

strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue projecting from the end, and upwardly offset from the plane, of said movable strip, and a locking member pivotally supported upon the other of said strips having a hooked arm adapted to embrace said tongue and a finger piece positioned in a plane at right angles to the plane of said hooked arm, and at substantially right angles to said hooked arm.

6. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue having a rounded end projecting from the end, and upwardly offset from the plane, of said movable strip, and a locking member pivotally supported upon the other of said strips having a hooked arm adapted to embrace said tongue and by engagement with its rounded end complete the closing movement of said movable strip.

7. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip having a longitudinally extended, upwardly formed rib engageable with the tongues upon said other strip and being of a thickness to be superimposed upon said base strip and to closely fit the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and

the leaves of a book, and both strips contribute towards the rigidity of the binder, and a pivot connecting one end of said strips.

8. A loose leaf binder embodying therein a sheet metal base strip, a plurality of arcuate posts formed integrally with, and projecting upwardly from, one edge of, and part way across, said base strip, a plurality of tongues formed integrally with, and projecting from the same edge of said base strip as said posts, said tongues overlaying, being parallel with and being spaced from said base strip, a movable sheet metal strip having a plurality of arcuate posts complementary to the posts upon said base strip and formed integrally with, and projecting upwardly from one edge of, said movable strip, said movable strip having a longitudinally extended, upwardly formed rib engageable with the tongues upon said other strip and being of a thickness to be superimposed upon said base strip and to closely fit

the space between same and said tongues, whereby said movable strip will be firmly held in close abutting relation to said base strip, turning movement of said movable strip in one direction is limited, lifting of the arcuate posts upon said movable strip in relation to the arcuate posts upon said base strip is prevented, said tongues are interposed between said movable strip and the leaves of a book, and both strips contribute towards the rigidity of the binder, a pivot connecting one end of said strips, and a locking mechanism comprising a tongue having a rounded end projecting from the end, and upwardly offset from the plane, of said movable strip, and a locking member pivotally supported upon the other of said strips having a hooked arm adapted to embrace said tongue and by engagement with its rounded end complete the closing movement of said movable strip.
